UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

TANDEM-SPRING DRAFT-RIGGING FOR RAILWAY-CARS.

SPECIFICATION forming part of Letters Patent No. 769,225, dated September 6, 1904.

Application filed February 24, 1904. Serial No. 195,012. (No model.)

To all whom it may concern:

Be it known that I, WILLIAM H. MINER, a citizen of the United States, residing in Chicago, in the county of Cook and State of Illinois, have invented a new and useful Improvement in Tandem-Spring Draft-Riggings for Railway-Cars, of which the following is a specification.

My invention relates to improvements in tandem-spring draft-rigging for railway-cars.

The object of my invention is to provide a tandem-spring draft-rigging for railway-cars of a simple, strong, safe, and durable construction and composed of few parts.

My invention consists in the novel construction of parts and devices and in the novel combinations of parts and devices herein shown and described and by which this object or result is practically accomplished.

In the accompanying drawings, Figure 1 is a central vertical section of a tandem-spring draft-rigging embodying my invention. Fig. 2 is a plan view, partly in horizontal section, on line 2 2 of Fig. 1. Fig. 3 is a cross-section on line 3 3 of Fig. 2. Fig. 4 is a detail bottom view of the stop-casting. Fig. 5 is an enlarged detail section taken on line 5 5 of Fig. 6, and Fig. 6 is a section on line 6 6 of Fig. 5.

In the drawings, A A represent the longitudinal center sills or frame-pieces of the car, the same being illustrated as of ordinary steel-frame construction.

A' is the front sill; A², the buffer-plate; A³, the carry-iron.

B is the coupler, B' the draw-bar, B² the draw-bar extension or yoke, these parts being of any ordinary or suitable construction.

C c and C' c' are longitudinally - arranged tandem-springs arranged between the two pairs of followers D D' and D² D³.

F is the stop-casting, the same comprising two integral side plates F' F', united by an upper connecting-web F² and having flanges F³ F⁴ at right angles to each other to fit against the faces or flanges of the center sills A A and to which the stop-casting is secured by connecting rivets or bolts F⁵. The stop-casting F is also provided with a transverse

flange F⁶ at its front end, to which bolts F⁸ extend, connecting it with the cross-sill A' and buffer-plate A². The stop-casting F is furnished with four pairs of shoulders or stops f f, f' f', f² f², and f³ f³ for the followers to abut against. The two middle stops or shoulders f' f² have a connecting bridge or web f⁴. The two inwardly-extended webs or projections f⁴ f⁴ serve as a guide for the draw-bar yoke or extension B², while permitting the draw-bar to have the necessary laterally-swinging movement. The stop-casting F is rigidly secured to the sills A A by bolts or rivets f⁵.

G G are the lower removable guides, upon which the followers rest and reciprocate. These guides G G are secured to the stop-casting F by short removable bolts g g, which fit in laterally-extending slots f⁶ in the feet f⁷ of the stop-casting F and which bolts pass through holes g' in the removable guide-plates G. The feet f⁷ on the stop-casting have rectangular guide-ribs f⁸ to prevent the bolts from turning as the nuts g² are screwed home. A downwardly-projecting flange f⁹ on one of the feet f⁷ engages the edge of the guide-plate G, and thus prevents the guide-plates G and the bolts g from moving laterally after the bolts have once been inserted laterally in place and the nuts thereon screwed up.

As the two side plates F' F' are made in one integral piece or casting with the connecting-web F², great additional strength, rigidity, and safety are secured, while at the same time the parts or pieces of the draft-rigging as a whole are reduced in number.

I claim—

1. In a tandem-spring draft-rigging, the combination with a draw-bar and draw-bar extension, of a pair of tandem-arranged springs, two pairs of followers and a single stop-casting having two integral side plates, each with upright integral stops or shoulders for the followers, and each having a horizontally-projecting flange and an upwardly-projecting flange, substantially as specified.

2. In a tandem-spring draft-rigging, the combination with a draw-bar and draw-bar ex-

tension, of a pair of tandem-arranged springs, two pairs of followers and a single stop-casting having two integral side plates, each with upright integral stops or shoulders for the followers, and each having an upwardly-projecting flange and a horizontal flange fitting against and secured to the draft-sills and removable guide-plates to support and guide the followers, substantially as specified.

10 3. In a tandem-spring draft-rigging, the combination with a draw-bar and draw-bar extension, of a pair of tandem-arranged springs, two pairs of followers and a single stop-casting having two integral side plates, each with 15 integral stops or shoulders for the followers, and removable guide-plates to support and guide the followers, said stop-casting having laterally-slotted feet and short connecting-bolts fitting in the lateral slots of said feet for 20 removably securing said guide-plates to the stop-casting, substantially as specified.

4. In a tandem-spring draft-rigging, the combination with the draw-bar, draw-bar extension, tandem springs and followers, of a 25 stop-casting having two integral side plates each furnished with stops for the followers, removable guide-plates to support the followers, and short connecting-bolts extending through said guide-plates and fitting in lateral slots in 30 the stop-casting, substantially as specified.

5. In a tandem-spring draft-rigging, the combination with the draw-bar, draw-bar extension, tandem springs and followers, of a stop-casting having two integral side plates

each furnished with stops for the followers, removable guide-plates to support the followers, and short connecting-bolts extending through said guide-plates and fitting in lateral slots in the stop-casting, said stop-casting being also provided with ribs to receive the heads of said 40 connecting-bolts and prevent the same from turning, substantially as specified.

6. In a tandem-spring draft-rigging, the combination with the draw-bar, draw-bar extension, tandem springs and followers, of a 45 stop-casting having two integral side plates each furnished with stops for the followers, removable guide-plates to support the followers, and short connecting-bolts extending through said guide-plates and fitting in lateral slots in 50 the stop-casting, said stop-casting having flanges engaging said guide-plates to prevent lateral movements of the bolts or guide-plates after the bolts are screwed home, substantially as specified.

7. In a tandem-spring draft-rigging, the combination with a draw-bar and draw-bar extension, of a pair of tandem-arranged springs, two pairs of followers and a single stop-casting having two integral side plates, each with 60 integral stops or shoulders for the followers, said stop-casting having a transverse flange at its front end, and bolts connecting the same with the cross-sill, substantially as specified.

WILLIAM H. MINER.
